FIG. 2.

Patented Feb. 5, 1889.

UNITED STATES PATENT OFFICE.

DEWITT C. BASSETT, OF WOONSOCKET, DAKOTA TERRITORY.

CAR-COUPING.

SPECIFICATION forming part of Letters Patent No. 397,412, dated February 5, 1889.

Application filed August 16, 1888. Serial No. 282,878. (No model.)

To all whom it may concern:

Be it known that I, DEWITT C. BASSETT, a citizen of the United States, residing at Woonsocket, in the county of Sanborn and Territory of Dakota, have invented certain new and useful Improvements in Car-Couplings; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention relates to car-couplings; and it consists in the novel construction and combination of the parts, as hereinafter fully described and claimed, whereby the train-men may couple or uncouple the cars without going between them.

In the drawings, Figure 1 is a side view of the ends of two cars provided with couplings according to this invention. Fig. 2 is an end view of one of the cars.

25 Each car has a bumper, A, centrally secured to its end, and provided with a pocket, a, for the link.

B is the link, and C is a link-pin, which passes through each of the bumpers A and secures the link in position. The upper part of pin C is secured to the cross-bar D, to the ends of which are secured the guide-rods E by the nuts e. The said guide-rods are adapted to slide vertically through holes in the bumper 30 on each side of the pocket a; and D' is a cross-bar secured to the lower ends of the said guide-bars by the nuts e'. The upper and lower ends of the guide-bars E are screw-

threaded, so that the said nuts e e' may be screwed upon them.

40 F is a long rod projecting upwardly from the top of the pin C and supported by the brackets F', secured to the frame of the car. A handle, f, is provided at the top of rod F, so that the pin C may be operated from the 45 roof of the car.

G G are chains or cords which are secured to the stud g, which projects from the pin C. These chains are carried over the pulleys H, journaled in the bracket H', which is secured 50 to the end of the car some distance above the top of the pin. Each chain is provided with an end ring, i, and each end is supported by a bracket, I, attached to the end of the car close to the side. When the chain is 55 pulled, so as to raise the pin C and uncouple the cars, the ring i and the end of the chain are allowed to hang down, as indicated by the dotted line in Fig. 2.

60 What I claim is—

In a car-coupling, the combination of the bumper, the vertical guide-rods working in the sides of the said bumper, the upper and lower cross-bars connected to said guide-rods, the coupling-pin attached to and depending 65 from the upper one of said cross-bars, the stud g, projecting from said pin, the chains connected at their inner ends to said stud, and the rod secured to the upper end of said pin, substantially as described.

70 In testimony whereof I affix my signature in presence of two witnesses.

DEWITT C. BASSETT.

Witnesses:

J. E. CARPENTER,
W. SCOTT SNYDER.
